UNITED STATES PATENT OFFICE

JOHN GIORDANO, OF SAN FRANCISCO, CALIFORNIA

TILE-ROOF CLOSURE

Application filed June 30, 1928. Serial No. 289,442.

The present invention relates to improvements in closures for tile roofs. A standard type of tile roof is made to present a wavy form so as to leave openings, particularly at the lower end of a slanting roof in which birds like to roost, much to the inconvenience of the owner of the property. It is the object of the present invention to provide a simple means for closing these openings, which may be very easily applied after the roof has been finished and which is provided with means for holding it in place after insertion.

It is further proposed to provide a means of this character which can be made very cheaply and handled very easily.

Further objects and advantages of my invention will appear as the specification proceeds.

20 The preferred form of my invention is illustrated in the accompanying drawing in which

Figure 1 shows in perspective view my invention as applied to the lower end of a tile roof;

Figure 2, a front view of my device;

Figure 3, a section taken along line 3—3 of Figure 2;

Figure 4, a plan view of my device; and

30 Figure 5, a side view of my device shown in place under the tiles of a roof.

While I have shown only the preferred form of the invention, I wish to have it understood that various changes or modifications may be made within the scope of the claims hereto attached without departing from the spirit of the invention.

In Figure 1 is shown the general situation in which my invention is to be used. A tile roof consisting of arched tiles 1 is supported on a sheathing 3, the tiles being arranged in the conventional manner so as to leave arched openings 4 at the lower ends which are favored by the birds for their roosts.

45 My closure for these openings comprises a closure plate 6 formed to substantially close the openings when inserted in an upright position.

50 This closure plate 6 has, extending from the bottom edge thereof, a base plate 7 which

may be fastened in any suitable manner as by means of clips 8 extending through perforations 9 in the closure plate and preferably fastened permanently. While any suitable means may be used for fastening the base plate 7 to the closure plate 6, it should be understood that the connection should be somewhat resilient so that if the closure plate is pressed downward or collapsed over the base plate for insertion into the opening 4, it will automatically return into an approximately upright position, so that the two plates co-operate in holding the closure plate in its position.

The base plate is corrugated as shown at 11 and the closure plate 6 has a brace 12 extending downwardly therefrom, adapted to ride over the corrugations 11 as the closure plate straightens out and to interlock with one of the corrugations when the closure plate has reached its final position.

The manner of using my device will be readily understood from the foregoing description.

Referring to Figure 3, the operator lifts 75 the brace 12 so that the lower end thereof is free of its engagement with the corrugations 11 and then presses the closure plate 6 downward upon the base plate 7. Holding the device in this position he introduces it into the opening 4 with the free end of the base plate in advance. Due to the tilted position of the closure plate 6, this operation is comparatively easy although the closure plate slightly exceeds in size the opening 4.

80 After the closure plate has reached a position well inside the tile structure, as shown in Figure 1, and in Figure 5, the operator releases his hold on the device with the result that the closure plate will straighten out and assume the almost vertical position of Figure 5, the whole device clamping itself in place. While the closure plate straightens itself, the brace 12 rides over the corrugations 11 and finally interlocks with one of the corrugations 85 when the closure plate has reached its end position. This plate is now firmly held in its place and effectively bars birds from entering the opening and building their nests therein.

I claim:

1. In combination with a tile roof, a closure plate for an open end thereof having a base plate resiliently fastened to the bottom edge, so as to allow the closure plate to be partly collapsed upon the base plate for insertion into the opening and to automatically rise into active position after insertion.
2. In combination with a tile roof, a closure plate for an open end thereof having a base plate resiliently fastened to the bottom edge, so as to allow the closure plate to be partly collapsed upon the base plate for insertion into the opening and to automatically rise into active position after insertion, a plurality of corrugations on the base plate and a brace extending from the closure plate adapted to ride over the corrugations as the closure plate rises and to interlock with one of them when the closure plate reaches its final position.
3. In combination with a tile roof, a closure plate for an end opening thereof having resilient means for holding the same in place, the resilient means being adapted to yield for facilitating the insertion of the closure plate, and having automatically operating means for positively locking the closure plate in its final position.

JOHN GIORDANO.
